a corporation of New York**

Application April 8, 1954, Serial No. 29,926

Term of patent 14 years

(Cl. D91—4)

To all whom it may concern:

Be it known that I, Curt Reimann, a citizen of the United States, residing in Springfield Gardens, county of Queens, and State of New York, have invented a new, original, and ornamental Design for a Push-Back Water Filler, of which the following is a specification, reference being had to the accompanying drawing, forming a part thereof, wherein:

Fig. 1 is a top elevational view of a push-back water filler showing my design;

Fig. 2 is a side elevational view thereof;

Fig. 3 is a front elevational view thereof;

Fig. 4 is a rear elevational view thereof; and
Fig. 5 is a bottom elevational view thereof.

I claim:
The design for a push-back water filler, substantially as shown.
